(57) **CLAIM**

The ornamental design for an lady bug soap bar maker, as shown and described.

DESCRIPTION

FIG. 1 is a front perspective view of the lady bug soap bar maker.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side view thereof; and,

FIG. 7 is a left side view thereof.

The broken lines of the electrical cord and the on/off button are included for the purpose of illustrating environment and form no part of the claimed design.

The claimed lady bug soap bar maker is used for reprocessing waste soap chips into new soap bars in the shape of a lady bug.
